(57) **CLAIM**

The ornamental design for a cord stopper as shown and described.

DESCRIPTION

FIG. 1 is a perspective view of a first configuration of a cord stopper showing my new design;

FIG. 2 is a front view of my new design as configured in FIG. 1;

FIG. 3 is a back view of my new design as configured in FIG. 1;

FIG. 4 is a left side view of my new design as configured in FIG. 1;

FIG. 5 is a right side view of my new design as configured in FIG. 1;

FIG. 6 is a top view of my new design as configured in FIG. 1;

FIG. 7 is a bottom view of my new design as configured in FIG. 1;

FIG. 8 is a cross-sectional view of my new design as configured in FIG. 1;

FIG. 9 is a schematic view of two cords passing through the cord stopper of the first configuration of FIG. 1,

FIG. 10 is a perspective view of a second configuration of the cord stopper showing my new design;

FIG. 11 is a front view of my new design as configured in FIG. 10;

FIG. 12 is a back view of my new design as configured in FIG. 10;

FIG. 13 is a left side view of my new design as configured in FIG. 10;

FIG. 14 is a right side view of my new design as configured in FIG. 10;

FIG. 15 is a top view of my new design as configured in FIG. 10;

FIG. 16 is a bottom view of my new design as configured in FIG. 10; and,

(Continued)

FIG. 17 is a cross-sectional view of my new design as configured in FIG. 10. The dotted lines are for illustrative purposes only and form no part of the claimed design.

1 Claim, 11 Drawing Sheets
